Primary Examiner — Thomas Johannes(74) *Attorney, Agent, or Firm* — Nixon & Vanderhye, P.C.(57) **CLAIM**

The ornamental designs for an electric connector, as shown and described.

DESCRIPTION

FIG. 1 is a front, top and right perspective view of an electric connector of our new design;

FIG. 2 is a rear, bottom and right perspective view thereof;

FIG. 3 is a front view thereof;

FIG. 4 is a rear view thereof;

FIG. 5 is a top plan view thereof;

FIG. 6 is a bottom plan view thereof; and,

FIG. 7 is a left side view thereof, a right side view being a mirror image thereof.

The broken line portion of the figure drawings is included to show unclaimed subject matter only and forms no part of the claimed design.
